Claims priority, application Republic of South Africa
Apr. 11, 1962

Term of patent 14 years

(Cl. D58—8)

Fig. 1

FIG. 1 is a side elevational view of a bottle, showing my new design.

FIG. 2 is perspective view thereof; and

FIG. 3 is a top plan view thereof.

The dominant features of my design reside in the portions shown in full lines.

I claim:

The ornamental design for a bottle or similar article, as shown and described.
